ABSTRACT OF THE DISCLOSURE

A solid bleaching mixture of a peroxygen compound such as sodium perborate tetrahydrate, sodium perborate monohydrate, or sodium monopersulfate, and an alkalinity booster such as sodium carbonate, sodium silicate or trisodium phosphate, effectively removes stains from household laundry when the mixture is added to the wash water in an amount which provides between about 50 and 150 parts per million available oxygen and a pH between about 10 and 12. When between about 50 and 500 parts per million of a surfactant, and between about 5 and 25 parts per million of an anti-deposition agent such as carboxymethyl cellulose or polyvinyl pyrrolidone are added to the wash water either together with the bleaching mixture or separately, the laundering is particularly effective. A sequestering agent for softening water, such as sodium tripolyphosphate may be included.

BACKGROUND OF THE INVENTION

Many bleaches have been used for home laundry purposes. Chlorine bleaches are excellent stain removers. However, the liquid hypochlorite bleaches must be packaged in bottles, and the chlorinated cyanuric acid bleaches are relatively expensive. Furthermore, chlorine bleaches must be used with care when bleaching protein fibers, such as silk, wool and mohair.

In an attempt to provide a solid stain remover for use in the home laundry, proteolytic enzymes have been mixed with packaged detergents. However, such enzymes are of limited effectiveness, since they are primarily effective only against protein stains, such as blood.

Peroxygen bleaching agents are known and employed in the textile manufacturing art for the removal or reduction of undesirable natural color bodies from new fabrics, yarns and fibrous materials. The means and conditions necessary to effect this purpose are in general severe in terms of temperatures, pressures and operating methods, and they include numerous stages and manipulations and are not practical for household use.

The wash cycle in an automatic household laundry unit is normally run at a temperature ranging from about 80° F. to 140° F. and at a pH below about 10. In the absence of suitable additives such as activators, catalysts, and the like as known in the art, perborate-containing bleaches appear to be ineffective or require impractically long contact times for the treatment of household laundry at such temperatures and pH values. The incorporation, on the other hand, of activators, catalysts, and the like in a solid bleach composition is undesirable for many reasons including cost, added process burden, and product stability on aging.

SUMMARY OF THE INVENTION

It has now been found that a solid, granular bleaching mixture of a peroxygen compound selected from the group consisting of sodium perborate, sodium monopersulfate, and mixtures thereof, and an alkalinity booster selected from the group consisting of sodium carbonate, sodium silicate trisodium phosphate and mixtures thereof, pro-

2

vides unusually effective bleaching under home laundry conditions when the peroxygen compound and alkalinity booster are proportioned so that the alkalinity booster provides a pH of between about 10 and 12 when a solution of the bleaching mixture contains between about 50 and 150 parts per million available oxygen. The addition of between about 50 and 500 parts per million of a surfactant, and between 5 and 25 parts per million of an anti-deposition agent, either intermixed with the bleaching mixture in the dry form or introduced separately into the wash water provides particularly effective washing and bleaching. Advantageously a sequestering agent is also incorporated for softening the wash water in the laundering process.

The instant bleaching mixture is dry and granular. It may be packaged and stored in any porous paperboard container without a vapor barrier, and yet it remains a readily pourable mixture which is convenient for use in the home laundry.

Surprisingly the compositions hereof are effective bleaching agents for household laundry uses in the relatively short, i.e. 10 to 20 minute, cleaning cycles of automatic household laundry units in the absence of added acylated organic nitrogenous activators such as N-benzoyl succinimide (see U.S. Pat. No. 3,061,550), acyl organoamides (see U.S. Pat. No. 3,177,148), carboxylic acid amides (see U.S. Pat. No. 2,898,181) and polyarylamines (see U.S. Pat. No. 3,163,606); of enhancing agents such as sodium p-acetoxybenzene sulfonate (see U.S. Pat. No. 3,185,649); of transition metal cationic catalysts (see U.S. Pat. No. 3,398,096); or of modified organic acid anhydrides (see for example U.S. Pat. No. 3,298,775).

By household laundry is meant clothing and fabrics made of natural and synthetic fibers and mixtures thereof, particularly the cotton, linen and nylon and polyester-type textiles normally used in the home.

By the bleaching and/or treatment of household laundry as used herein is meant the removal or substantial reduction of stain, i.e. foreign coloring matter, from clothing and household textiles.

BRIEF DESCRIPTION OF THE DRAWING

The drawing is a graph which illustrates the total change in color of swatches stained with ink as the available oxygen content provided by the peroxygen compound is increased. The graph contains four curves for four different pH values.

DESCRIPTION OF THE PREFERRED EMBODIMENTS

In greater detail the available oxygen which provides active bleaching is obtained from a solid peroxygen compound preferably selected from the group consisting of sodium perborate, sodium monopersulfate and mixtures thereof. The sodium perborate may be in the form of the tetrahydrate or the monohydrate. Sodium perborate tetrahydrate provides about 10.4 percent available oxygen, sodium perborate monohydrate provides about 16.0 percent available oxygen, and sodium monopersulfate provides about 4.5 percent of its weight available oxygen when dissolved in the wash water.

The alkalinity booster is provided by sodium carbonate, sodium silicate, trisodium phosphate or mixtures thereof. A sufficient amount of the dry alkalinity booster is mixed with the peroxygen compound to provide a pH of between 10 and 12 when between about 50 and 150 parts per million available oxygen is provided to the wash water by the peroxygen compound. It is apparent that the ratio of peroxygen compound to alkalinity booster will vary greatly because of the different amounts of available oxygen provided by the various peroxygen compounds, and

the difference in alkalinity of the alkalinity boosters as well as the buffering effect of the surfactant and/or surfactant builders. However, the ratio of alkalinity booster to peroxygen compound which provides the desired pH range for different alkalinity boosters and peroxygen compounds may readily be determined in each case by simple pH measurements.

A conventional sequestering agent for softening the water may be added to the bleaching mixture of the peroxygen compound and the alkalinity mixture to enhance the washing effect. Suitable sequestering agents include sodium tripolyphosphate, sodium nitrilo acetate and ethylene diamine tetracetic acid. An amount of sequestering agent proportioned to provide between 0 and 2000 parts per million sequestering agent for each 50 to 150 parts per million available oxygen may be included in the dry bleaching mixture.

In a preferred embodiment of solid free flowing bleaching composition is prepared by dry mixing particulate granules of sodium carbonate, sodium perborate tetrahydrate and sodium tripolyphosphate. Optionally and for aesthetic reasons minor amounts in the range 0.01 to 0.2 part each, of conventional additives may be included in the mix, such as for example: (1) ultramarine blue coloring agent (2) perfume, (3) antidust agents, and (4) optical brighteners. Inert fillers such as sodium sulfate may also be added.

The solid compositions of the instant invention may be formulated as well-blended, i.e. essentially homogeneous, granular mixes or may be tableted in a variety of sizes and shapes as desired. Whatever the form, the solid mix rapidly dissolves in water.

A particular advantage of the solid bleaching composites of the present invention is that they can be effectively applied for stain removal from household laundry during the washing cycle. Detergents or surfactants in general as known in the art are satisfactory for use in conjunction with the instant composites. In a corollary aspect herein these surfactants can be added as a fourth major component to the present dry bleach-containing mixtures. Either anionic or nonionic detergents are used in an amount sufficient to provide between about 50 and 500 parts per million surfactant in the wash water when the amount of peroxygen compound is between about 50 and 150 parts per million. Representative surfactants which may be used in this manner include alkylbenzene sulfonates and sulfated alcohol-ethoxylates, and such nonionics as alkyl ethoxylates.

An anti-deposition agent is added to the wash water along with the surfactant. The anti-deposition agent may be added separately or in a solid mixture with the peroxygen bleaching composition. Suitable anti-deposition agents include polyvinyl pyrrolidone, carboxymethyl cellulose and polyvinyl alcohol. Between about 5 and 25 parts per million anti-deposition agent is used in the wash water.

Extremely effective bleaching and washing is provided by the following home laundry wash water composition:

Alkalinity booster: pH 10 to 12
Peroxygen compound: 50 to 150 p.p.m.
Sequestering agent: 0 to 2000 p.p.m.
Surfactant: 50 to 500 p.p.m.
Anti-deposition agent: 5 to 25 p.p.m.

The pH provided by the alkalinity booster is an important factor. Below a pH of 10, the oxygen is released too slowly from the peroxygen compound and the bleaching is not very effective. Above a pH of 12, damage to hands and clothes may occur.

Also, bleaching is not very effective when the amount of available oxygen provided by the peroxygen compound is less than 50 parts per million. Above about 150 parts per million, the extra oxygen is of little additional value.

The sequestering agent is not essential, depending upon the nature of the water. However, it is of great value in enhancing washing in hard water areas.

When the amount of surfactant is less than about 50

parts per million, the washing is not complete in a normal wash cycle. Above about 500 parts per million the surfactant is wasted and oversudsing may occur. Also, a rinsing problem may develop with resultant yellowing of fabrics when too much surfactant is used.

Throughout the specification, all amounts are stated in terms of weight.

10 A granular, free-flowing solid bleaching mixture of sodium carbonate, sodium perborate tetrahydrate and sodium tripolyphosphate was prepared by mixing the following components in a commercial mixing unit for solids:

	Weight ratio
Na ₂ CO ₃	53.55
NaBO ₃ ·4H ₂ O	30.00
Na ₅ P ₃ O ₁₀	16.00

20 Small amounts of ultramarine blue coloring agent, perfume antidust agents and commercial optical brighteners totaling 0.45 part by weight were also added to the solid mixture to bring the total to 100 parts by weight.

25 One-half cup (about 120 grams) of the solid bleaching mixture was added to a household washing machine containing 17 gallons or about 64,000 ml. water. This provided about 36 grams of sodium perborate to the wash water resulting in about

$$30 \frac{3.6}{64,000} = 56.5 \text{ p.p.m.}$$

35 available oxygen, and a pH of about 10.2 measured after addition of the detergent. The detergent mixture added to the wash water provided the following additional ingredients to the water:

	P.p.m.
Alkylbenzene sulfonate	320
Sodium tripolyphosphate	800
Sodium metasilicate	95
Sodium sulfate	375
Carboxymethyl cellulose	10

45 Clothes stained with ink, blood and mustard were placed in the wash water. The clothes were washed for 10 minutes at a water temperature of about 120° F., and dried in a tumbler drier for about 20 to 25 minutes. The stain removal was excellent.

50 Also, tests were conducted at varying available oxygen contents and at different pH levels and the bleaching effectiveness of the bleaching mixtures hereof was measured quantitatively. Representative stains were padded onto commercially available unbleached cotton muslin test cloth. The stained cloth was cut into swatches, each swatch was numbered and Hunter D25 Color Difference meter readings were made on the test fabrics. There were then attached to carrier towels and the assembly was washed, dried, pressed wrinkle-free and reread on the color meter. The total change in the color values between 55 unwashed and washed test swatches indicated the amount of stain removed during the test as follows:

$$60 \Delta E = [(\Delta L)^2 + (\Delta a)^2 + (\Delta b)^2]^{1/2}$$

where

E=Total change in color

L=Mean change in lightness value

a=Mean change in green/red value

b=Mean change in blue/yellow value

70 The water washing-bleaching operation was carried out in a commercial automatic laundry unit having a normal cleaning cycle of 10 minutes and employing a cleaning solution volume of 16.5 gallons (120 p.p.m. water hard-

ness) at 120 ± 3 ° F. One hundred grams of a representative detergent, a linear alkylbenzene sulfonate composite:

	Parts (wt.)
Linear alkylbenzene sulfonate	20
Sodium tripolyphosphate	50
Sodium metasilicate	6
Sodium sulfate	23.5
Sodium carboxymethyl cellulose	0.5
	100

plus the carrier towels and ballast towels sufficient to provide a five-pound load, were charged to the washer followed by a solid granular mixture of sodium perborate tetrahydrate, sodium carbonate and sodium tripolyphosphate proportioned to provide the pH and available oxygen values set forth in Table I below. Drying, ironing and reading under standardized conditions completed the test.

Permanent blue-black ink is a representative stain encountered in household laundry and was, for that reason, selected for the test with the following results which are plotted in graph form in the drawing:

TABLE I

Stain	pH	Available O ₂	E	Stain removal
Permanent blue-black ink.	9	0	51.1	Poor.
	20	56.1	Do.	
	40	58.0	Do.	
	60	58.0	Do.	
	80	54.6	Do.	
	100	54.6	Do.	
10.0	0	52.3	Poor.	
	20	53.7	Do.	
	40	56.8	Do.	
	60	65.5	Fair.	
	80	74.9	Excellent.	
	100	76.5	Do.	
10.5	0	50.6	Poor.	
	20	56.7	Do.	
	40	64.6	Fair.	
	60	67.1	Good.	
	80	78.8	Excellent.	
	100	76.7	Do.	
11.0	0	51.4	Poor.	
	20	60.1	Do.	
	40	68.3	Fair.	
	60	74.5	Excellent.	
	80	77.7	Do.	
	100	76.1	Do.	

The foregoing examples demonstrate that the bleach composites herein are effective stain removal agents for use in automatic household laundry at temperatures substantially below 140° F.

What is claimed is:

1. The method of bleaching stains in household laundry which comprises adding to wash water containing said laundry a solid, soapless, granular bleaching and stain removing mixture consisting essentially of a peroxygen compound selected from the group consisting of sodium perborate, sodium monopersulfate, and mixtures thereof; and an alkalinity booster selected from the group consisting of sodium carbonate, trisodium phosphate, water soluble sodium silicate and mixtures thereof; said alkalinity booster being added in an amount to provide a pH in the wash water of between about 10 and 12 and said peroxygen compound being added in an amount to provide between 50 and 150 parts per million available oxygen in the wash water.
2. The method of claim 1 wherein said solid mixture also contains sodium tripolyphosphate present in an amount up to 2000 parts per million for each 50 to 150 parts per million of available oxygen.
